UNITED STATES PATENT OFFICE.

HERMON L. VAN VALKENBURG, OF MILWAUKEE, WISCONSIN, ASSIGNOR TO INDUSTRIAL CONTROLLER COMPANY, OF MILWAUKEE, WISCONSIN, A CORPORATION OF WISCONSIN.

STARTING SWITCH.

Application filed December 30, 1919. Serial No. 348,332.

To all whom it may concern:

Be it known that I, HERMON L. VAN VALKENBURG, a citizen of the United States, residing at Milwaukee, in the county of Milwaukee and State of Wisconsin, have invented a certain new and useful Improvement in Starting Switches, of which the following is a specification.

My invention relates to starters for electric motors. In starting small motors, there is no harm in throwing the motor terminals directly across the line in the first instance, but when this is done the initial inrush of current is usually so great as to blow the fuses. It has, therefore, become recognized as good practice to first connect the motor to the line thru a path which does not include the fuses and then when the motor has attained sufficient speed to generate the necessary counter E. M. F., change the connections so that the current will thereafter be supplied thru the fuses. One object of my invention is to provide apparatus so constructed as to compel the operator to start the motor in the manner stated. According to the design illustrated, when the operator moves the handle from off position to starting position, it first causes a subsidiary switch to close, thus establishing a by pass or shunt around the fuse. The continued movement of the handle then closes the main switch and the current passes direct from the source of supply to the motor. The handle is now in starting position. The operator then moves the handle part way backward, (or he may simply release it, as the handle tends automatically to move part way back) whereupon the subsidiary switch opens the shunt circuit and the current flows thru the fuses and main switch. The handle is now in running position. It is left here until it is desired to stop the motor, whereupon the operator moves the handle still further backward to initial or off position thus opening the main switch. My purpose is to render the mechanism automatic with respect to the most important steps or at least to make it impossible to operate it in improper sequence. Another object of the invention is to provide protective mechanism by enclosing the operating parts in a box or housing furnished with a cover and supplying interlocking mechanism whereby the switch cannot be closed until the door has

been closed and the door cannot be opened 55 without first opening the switch.

I obtain my objects by the mechanism illustrated in the accompanying drawings in which,

Figure 1 is a general perspective view 60 showing the outside of the apparatus. This view shows the operating handle and indicates the off, start, and run positions thereof.

Figure 2 is a perspective view of the apparatus, a portion of the box and cover and 65 some of the operating parts being broken away to render the construction more apparent.

Figure 3 is a front elevation of the parts shown in Figure 2. 70

Figure 4 is a side elevation of the operating parts showing the position which they occupy when the handle is in off position.

Figure 5 is similar to Figure 4, but shows the position which the parts will occupy 75 when the handle is moved part way toward start position. The subsidiary switch has been closed but the main switch is still open.

Figure 6 is similar to Figure 5, but shows the position which the parts occupy when 80 the handle is in start position. Here both switches are closed.

Figure 7 shows the position which the parts will occupy when the handle has moved backward from starting to running 85 position.

Figure 8 shows the parts in the same position as in Figure 7, but certain elements are shown in section in order to give a better understanding of the parts. 90

Figure 9 is a diagram illustrating the principle of the apparatus.

Like numerals denote like parts throughout the several views.

In the form selected to illustrate the invention, the operating parts are enclosed within a box 1 made usually of metal and in the present instance having flanges 2, 2 which may be fastened against a wall or other stationary object. It has a sliding 100 cover 3 which for convenience may be provided with a handle 4 for opening and closing it. By reference to Figures 1 and 2, it will be seen that provision is also made whereby the box can be padlocked, the cover 105 having a flange 6 suitably apertured to accommodate a post 7 rising from the top of the box. This post is apertured and the re-

sult is that by passing the bow of a padlock thru it when the cover is closed, the cover will remain locked until the padlock is removed. The flange 6 also furnishes a stop 5 for limiting the descent of the cover.

The parts of the switch proper are operated from a point outside of the box by means of a handle 10 which, as best shown in Figure 3, is journaled in one of the side 10 walls of the box and is rigidly connected to a bail 11. The bail is located within the box and is coaxial with the operating handle. It has two side arms 13, one of which is pivotally supported on a pin 12 fastened to 15 the wall of the box.

Fastened to the back of the inside of the box is a panel 15 of slate or other insulating material. Near the bottom of this panel are binding screws 16 for connection to the sup- 20 ply conductors 17 shown in Figure 4. The illustrated device is for a three wire system of distribution and is therefore a three pole switch and the binding screws are three in number. Similarly, there are three binding 25 screws 18 for the distributing conductors 19; but it will be understood that the number of poles is immaterial. The screws 16 hold the conductors 17 in contact with terminals 21 which are electrically connected 30 to stationary conductive brackets 22 provided with fuse clips 23. Said terminals also have contacts 24 adapted to be engaged by discs 25 whose function is to bridge the 35 gap between said contacts and the corresponding contacts 26 located opposite to them. The contacts 26 form part of the conductive strips 27 and are electrically connected to stationary conductive brackets 28 provided with fuse clips 30, the latter being 40 adapted to cooperate with the clip 23 to hold the fuses 31. It will be evident that when the discs 25 are out of engagement with the contacts 24, 26, as shown in Figure 4, current will pass from the supply conductors thru 45 the brackets, clips, and fuses to the strips 27, but when the discs are in engagement with said contacts, the fuses will be short circuited and the discs will bridge the gap between the contacts and permit the current 50 to pass directly from one to the other.

The strips 27 are electrically connected to conductive posts 35 to which the switch blades 36 are pivoted. The pivotal axes of the switch blades are substantially in line 55 with the axis of the bail 11. Said blades are adapted to be rotated into engagement with the fixed jaws 38 which are electrically connected to the terminal strips 40. Strips 40 are electrically connected to the binding 60 screws 18. The switch blades are all fastened to the cross bar 43 which is of insulating material and of rigid construction and affords means for compelling the switch blades to operate in unison. Said cross bar 65 and blades are swung to open and closed po-

sition by means of flat bars 45 which are rigidly fastened to said bar and have fingers 46 at the upper end and fingers 47 at the lower end. By preference, the bars are curved so as to be approximately concentric 70

with the axis of the bail and of the switch blades. Said bars in the present design, are two in number and they are bolted or otherwise rigidly fastened to the cross bar. Their fingers 46 and 47 are so placed to be in the 75 path of the cross bar of bail 11 as the latter rotates about its axis; and the proportions are such that when the bail is swung to its uppermost position, as shown in Figure 6, the switch blades 36 will engage the jaws 38 80 and the switch will be closed. After this the bail may be swung down for a considerable distance before it engages the lower fingers 47. A further downward movement of the bail after it has engaged the fingers 47 85 swings the switch blades out of engagement with the jaws and opens the switch. The first mentioned position in which the bail is at its highest point corresponds to the "start" 90 position as will presently more fully appear.

I have now described the opening and closing of the main switch by means of the bail and the fingers 46 and 47 of the segmental bars 45. I will next describe the operation of the subsidiary switch. This has discs 25 which are freely slidable upon rods 50 rigidly secured to but completely insulated from a cross bar 52. While the precise method of insulation is immaterial, it is accomplished in the present design largely by 100 means of the insulating washers 53. The rods are surrounded by helical compression springs 55 one end of which abuts the lower washers and the other end bears against the discs to yieldingly hold them in contact with the stop pins 57 at the lower end of the rods. Cross bar 52 forms part of a second bail having side arms 60 pivoted upon the stationary pins 61 secured to the sides of the box near the top. The discs 25 are moved 105 into and out of engagement with the contacts 24, 26 by the movements of this second bail about its axis. This bail is biased to open position by helical springs 64, one end of which abuts the top of the box and the 110 other is anchored to the bail arms 60. The second bail is operated by the main bail 11, the side arms 13 of which lie in front of and are adapted to engage the lugs 65 on arms 60 to promote the wearing qualities of the 115 apparatus. These lugs may be rounded at the lower end where first engaged by the bail arms 13, see Figures 4 to 8. The parts are so arranged and proportioned that when the operating handle and main bail are in off position, which in the present design is the lowermost position, the main bail will be out of engagement with the lugs 65 and the springs 64 will hold the discs 25 in open 120 position out of engagement with their con- 125

tacts 24, 26, but when the handle is rotated upward toward start position, the side arms 13 will engage the lugs 65 and move the discs 25 into engagement with said contacts and 5 short circuit the fuses. This condition occurs before the cross arm 11 of the main bail has closed the main switch. Consequently when the main bail has moved far enough to actually close the main switch the current 10 will flow, not thru the fuses, but around them: that is, thru a shunt or short circuiting path formed by the contacts 24, discs 25, and contacts 26.

The cycle of operation of the parts thus 15 far described is as follows: Assume that the operating handle 10 is in lowermost or off position in which case the parts will be in the positions shown in Figure 4. If now the operator wishes to start the motor, he 20 grasps the operating handle and moves it forward (in the present case, upward). As the handle advances, the main bail, which moves with it, engages the lugs 65 of the second bail and causes the latter to bring 25 the discs 25 into engagement with their contacts. The parts are now in the position shown in Figure 5. Incidentally during this movement the main bail "picks up" the main switch by engaging the fingers 46 which are 30 fastened to it. But the main switch does not close until the handle has reached starting position at the forward end of the travel. The parts are now in the position shown in 35 Figure 6 and the current passes from the supply conductors to the distributing conductors thru the short subsidiary switches 25 and the main switch blades 36. Consequently the fuses are protected against the initial inrush of current. The operator next 40 permits the handle to move in the reverse direction—that is, towards running position which in the present case is about half way between the start and off positions. As the handle moves backward the main bail 45 permits the springs 64 of the second bail to move the discs 25 out of engagement with the contacts 24, 26. The apparatus is then in running condition and the parts are in the positions shown in Figures 7 and 8. The 50 reverse movement of the main bail does not open the main switch at this time because the jaws 38 frictionally engage the switch blades and hold them in closed position. The operator may now remove his hands 55 from the handle and the motor will continue to run with current supplied thru the fuses. When he desires to stop the motor, he swings the handle down to off position which causes the main bail to engage the 60 fingers 47 and open the main switch. The parts then return to the position shown in Figure 4.

It is not necessary for the operator to consciously return the handle from start to 65 run position. All that is necessary is for

him to let go of the handle after he has moved it to start position, whereupon gravity and the action of the springs 64 will move it to start position where it will be arrested by the contact of the main bail 70 with the lower fingers 47. It will hence be evident that the device is incapable of misoperation for if the operator when intending to start simply moves the handle from off to run position the main switch will not 75 close and no current will be supplied to the motor. He must move the handle fully to start position before the motor will start at all and after he has done this, he need not make any movement other than to release 80 the handle. If left to itself, the apparatus will automatically assume running condition with the fuses in circuit.

It will be observed that in the form shown 85 when the handle is in off position the two switches are in the same condition—that is, open. Also that during the forward movement of the handle both switches change their condition, one after the other. Also that the handle moves part way backward 90 automatically and that in doing so it permits the subsidiary switch to open, but that friction holds the main switch closed. Also that while the subsidiary switch is first to operate when the handle is moving forward, 95 it is also the first to operate when the handle is moving backward. This is here made possible by the last motion of the handle relatively to the main switch due to the fact that the main bail does not pick up the fingers 47 until after it has moved a considerable distance backward and in the meantime permitted the subsidiary switch (discs 25) 100 to open.

In order that the electrical relationship 105 of the parts may be readily understood, reference is made to the diagram, Figure 9. In this figure the parts bear the same reference numerals as in the other figures, except that the counterpart of the circuit closing element 25 of the starting or subsidiary switch is conventionally illustrated by the element 25a. By referring to the diagram 110 it will be readily seen that the two switches are in series with each other and that the protective device 31 is arranged in shunt with the subsidiary or starting switch and is controlled by it.

Now referring to the locking mechanism 115 by which the cover is prevented from being opened when the switch is closed and the switch is prevented from being closed when the cover is open:

A lug 70 is screwed or otherwise fastened 120 to the inside of the cover near the lower end thereof. This lug is here shown to be approximately Z-shaped, one flange lying in contact with and being fastened to the cover as best shown in Figure 2. Under ordinary 125 conditions the only necessity for opening the 130

cover is to afford access to the fuses. I have so designed the lug that it will strike the top of the box as soon as the cover has risen far enough to afford access to the fuses. 5 This leaves the main switch contacts still covered and prevents the operator from attempting to make any repairs other than fuse manipulation unless he first deliberately removes the lug entirely. The lug thus 10 limits the movement of the cover toward open position. But the lug has other locking functions: Loosely pivoted upon the stationary pin 12 is a locking plate 75. When in normal non-acting position, as shown in 15 Figure 4, it lies entirely out of the path of the lug 70 and hence permits the cover to open. The plate is so designed that gravity tends to hold it in this non-acting position. At its upper edge the plate has a lug 76 20 adapted to be engaged and moved upward by one of the side arms 13 of the main bail. When the bail is in off position with the switches both open, the plate will permit the locking lug 70 to pass, and it will be ineffective 25 upon lug 76, but as said bail is moved forward it rotates the locking plate and causes it to move its locking edge 75^a into the path of the flange 70^a of the locking lug. This holds the cover closed. If the cover is 30 open the locking lug will occupy the position shown in dotted lines in Figure 4 and will obstruct the movement of the bail 11 and prevent it from closing the main switch. Thus the lug 70 locks the cover closed so 35 long as the switch is closed and locks the switch open so long as the cover is open.

As a matter of convenience, a lug 78 is 40 outstruck from plate 75. This prevents the main bail from swinging too far downward—that is, past off position. The same effect, however, but in a less advantageous way may be accomplished by fastening a bracket 79 on the outside of the box as shown in Figure 1.

45 Having thus described my invention what I claim as new and desire to secure by Letters Patent, is:—

1. A motor starter having a main switch, a subsidiary switch, a protective device in 50 series with the main switch and connected in shunt around the subsidiary switch, an operating handle, means operated by said handle in moving from initial off position to first close the subsidiary switch, and a 55 spring interposed between the handle and the circuit closing element of the subsidiary switch to enable the handle to continue its forward movement after the subsidiary switch is closed.

60 2. A motor starter having a main switch, a subsidiary switch in series with it, the subsidiary switch having a movable circuit closing element adapted to make butt contact when closed, a protective device in series 65 with the main switch and connected in shunt

around the subsidiary switch, an operating handle, means operated by said handle in moving forward from initial off position to first close the subsidiary switch, and a spring interposed between the handle and the circuit closing element of the subsidiary switch to enable the handle to continue its forward movement after the circuit closing element of the subsidiary switch has been closed. 75

3. A motor starter having a main switch, a subsidiary switch in series with the main switch, the subsidiary switch having a pair of stationary contacts and a flat circuit closing element adapted to move toward and 80 from the terminals in a direction approximately normal to the surface of the circuit closing element, a protective device in series with the main switch and connected in shunt around the subsidiary switch, an operating handle, means operated by said handle in moving forward from initial, off, position, to first move the circuit closing element of the subsidiary switch into engagement with its cooperating terminals, and a spring interposed between the handle and the circuit closing element of the subsidiary switch to enable the handle to continue its forward movement after the circuit closing element of the subsidiary switch has been brought 85 into engagement with its cooperating terminals. 90

4. In a motor starter, the combination of a main switch, a subsidiary switch, an operating handle, a bail for operating the subsidiary switch, a bail for operating the main switch, said bails being independently movable and one of them being operated by the handle, the other of said bails being adapted to be operated by the bail which is 100 operated by the handle, whereby the movements of said switches are independent to a limited extent, but interdependent as a 105 whole.

5. In a motor starter, the combination of a main switch, a subsidiary switch, a bail for operating the subsidiary switch, a second bail for operating the main switch, said bail being independently movable, one of 110 said bails being adapted to actuate the other, and an operating handle adapted to operate the bail-actuating bail. 115

6. In a motor starter, the combination of a main switch, a subsidiary switch, an operating handle, a bail for operating the subsidiary switch, a bail for operating the main switch, said bails being independently movable and one of them being operated by the handle, the other of said bails being adapted to be operated by the bail which is 120 operated by the handle, there being lost motion between the main switch and the bail which operates it. 125

7. A motor starter having a rotatable handle, a running switch having a circuit 130

10 closing element rotatable about the produced axis of the handle and actuated by the handle, and a starting switch having a circuit closing element rotatable about an independent axis, the circuit closing element of the running switch being adapted to engage the circuit closing element of the starting switch at a point at least halfway distant from the axis of the starting switch to thereby increase the leverage of the action.

8. A motor starter having a rotatable handle, a running switch having a circuit closing element rotatable about the produced axis of the handle and actuated by the handle, and a starting switch having a circuit closing element rotatable about an independent axis, the circuit closing element of the running switch being adapted to engage the circuit closing element of the starting switch at a point at least halfway distant from the axis of the starting switch to thereby increase the leverage of the action.

15 handle, and a starting switch having a circuit closing element rotatable about an independent axis, the circuit closing element of the running switch being adapted to engage the circuit closing element of the starting switch at a point at least halfway distant from the axis of the starting switch to thereby increase the leverage of the action, and the point of engagement on the circuit closing element of the running switch being nearer to the axis thereof than is the handle.

20 In witness whereof, I have hereunto subscribed my name.

HERMON L. VAN VALKENBURG.

In witness whereof, I have hereunto subscribed my name.
